UNITED STATES PATENT OFFICE

2,588,311

OIL WELL DRILLING APPARATUS

George P. Wagner, Mount Vernon, N. Y., assignor to The Engineering Development Company, Incorporated, doing business as Engineering Development Company, Incorporated, Dallas, Tex.

Application October 28, 1946, Serial No. 706,253

9 Claims. (Cl. 255—4)

1

The invention relates to oil well drilling apparatus, and more especially to turbine operated devices of this type.

The ordinary system of oil well drilling involves the rotation of a drill pipe or tubing at the bottom of which the drill bit is secured. During the drilling, mud is pumped downward into this pipe to remove the material loosened by the drill. The disadvantages of this procedure are well recognized, especially when great depths are to be reached. The inertia of the drill pipe is large, and its rotation requires considerable power. The strain placed on the pipe is very large, and the pipe must be strong and therefore heavy to prevent it from breaking. If the pipe does break, the expense of removing the broken part from the hole is extensive, and often this broken part cannot be removed so that a new hole must be started. Numerous other drawbacks are well known to those operating in this field.

Several proposals have been made for avoiding many of these difficulties by mounting a turbine in the lower end of the drill pipe, and attaching the bit to this turbine, the drilling mud being used as the driving medium for this turbine. Such turbines, however, have been complicated and expensive to construct and have not proven a solution to the problem. They have usually been difficult to repair, and especially hard to handle for persons not particularly skilled in the use of such machines, as is true of many oil field workers. As a result, most drilling is still carried out by the old conventional methods of rotary or cable tool drilling.

The primary object of the present invention is to provide a novel apparatus for oil well drilling which avoids the drawbacks of the conventional method, by the use of a construction which is practical in operation, and which is easy to build, simple to assemble, and readily repaired if any part is damaged. More especially, the invention contemplates the provision of a turbine driven device of this type which can be taken apart and put back together by a few relatively unskilled workers, so that repairs can be made on the spot without requiring special handling.

Another object of the invention is to provide an oil well drilling apparatus of the turbine type which is so constructed as to be useable at great depths, and under widely differing operating conditions.

Still another object of the invention is to provide a novel type of oil well drilling turbine, of the multistage type, which is more efficient in use than those heretofore proposed, and which

2

is formed of parts capable of being produced by simple machining operations, so that the cost of the device is reduced. The invention in this respect further contemplates a novel method of producing these turbine parts, and more particularly the outer parts of a turbine for oil well drilling in which the rotor parts are removable endwise from the stator parts.

One primary feature of the invention lies in the novel relation between the turbine rotor, to which the bit is attached, and through which the drilling mud passes after it has actuated the turbine, and the stator, which is secured to the lower end of the drill pipe. This arrangement is such that the rotor can be removed from within the stator longitudinally, without disassembling either part. For this purpose, the turbine, which must have a very considerable number of stages to be practical, is formed of a rotor part located wholly within a cylinder and a stator located completely without this cylinder; in contrast with usual oil well turbines in which the rotor blades and the stator blades overlap longitudinally of the device. The turbine is preferably formed of rotor discs or rings, of equal diameter, in the peripheral surfaces of which are cut grooves forming the turbine blades, these grooves being so shaped as to receive the mud fed to them in a direction substantially tangential to the ring surfaces and to reverse the direction of this flow, so as to impart energy to the rings; while at the same time the mud is directed downward to the next turbine stage, until it reaches the bottom of the turbine. The rotor rings turn within the stator rings, which are similarly formed to receive the mud from the rotor blades, reverse its direction, turn it downwardly, and feed it tangentially into the next lower set of rotor blades. The stator rings all have an internal diameter greater than the outside diameter of the rotor. With such an arrangement, the stator and rotor can be assembled separately, and the rotor then slipped into the stator, without the necessity of any accurate adjustments between the parts during this assembling operation, except to get an exact longitudinal positioning. The prior art devices have normally required an assembly of the stator and rotor parts alternately, with special adjustment at each stage. The present device does away with any such necessity, and thus makes the apparatus easier to assemble during manufacture and more readily repaired in the field.

In producing a turbine of this type, the cutting of the grooves in the inner faces of the outer, or

stator, rings presents difficulties. It is difficult to get a grinding or cutting wheel of the required size into the interior of the ring, and to give it the necessary support during the grinding operation. The present invention contemplates avoiding this trouble by forming the stator of a series of rings, one for each stage, but forming in the side faces of each ring one half of a stator blade, and then piling the rings together so that each blade is formed by mating halves in the adjacent side faces of two rings. It is then possible to form the half blades from the side of the ring, and it is entirely unnecessary to attempt to support and drive a grinding wheel in the interior of the ring.

A further object of the invention is to produce a durable machine capable of standing up under the rough usage usual in oil field operations, and not likely to be thrown out of adjustment by such usage. Still another object is to provide such a device which will operate for long periods even when secured on the end of a string of pipe stem of very great weight.

Further objects and advantages of the invention will appear more fully from the following description, particularly when taken in conjunction with the accompanying drawings which form a part thereof.

In the drawings:

Figure 1 is a vertical cross-section through an oil well showing the device of the present invention in use.

Figure 2 is a side elevation, partly in section, of the turbine drill.

Figure 3 is a cross-section on the line 3—3 of Fig. 1.

Figure 4 is an enlarged view of a part of the cross sectional portion of Figure 1, showing two each of the rotor and stator rings.

Figure 5 is a cross-section on the line 5—5 of Fig. 4.

Figure 6 is a cross-section on the line 6—6 of Fig. 5.

Figure 7 shows in elevation a part of the outside face of one of the rotor rings.

Figure 8 shows in side elevation a part of the inside face of one of the stator rings.

Figures 9 and 10 show, in side elevation and in plan view, respectively, the formation of one of the blade slots in a rotor ring.

Figures 11 and 12 are similar views showing the formation of a blade slot in one of the stator rings.

The device consists in general of a stator part 2 adapted to be secured to the lower end of a drill pipe 4, and a rotor part 6 adapted to carry any suitable type of drill bit 8.

The stator part is composed of a first hollow upper bearing section 10 internally threaded at its upper end to engage the lower end of drill pipe 4. The lower end of section 10 is reduced in diameter and is externally threaded to receive the internally threaded upper end of turbine section 12. The turbine section has an internal annular shoulder 14 and below this a second shoulder 16. A bearing 18 is mounted in the lower end of section 12.

Section 10 has an upwardly directed shoulder 20 upon which rests a spider consisting of a ring 22 having vertically disposed ribs 24 which engage the inner wall of section 10. A ring 26 is provided between the upper edge of the spider and the bottom end of the drill pipe. The lower end of the drill pipe, ring 26, and the part of section 10 below shoulder 28 have inclined slots 30.

32, 34 respectively, forming with the spaces between ribs 24 a fluid passage past the spider.

The spider at its lower end has an inwardly turned annular shoulder 36, and between this and ring 26 are held the outer members 38 of a radial and thrust bearing assembly. These consist of L-shaped elements arranged one above the other and formed of a suitable self-lubricating material. These are annular in shape and are keyed to the interior wall of the spider as at 40.

The rotor 6 has near its upper end a shoulder 42 on which rest the inner members 44 of the radial and thrust bearing, which are likewise annular and L-shaped and are keyed on the rotor body as at 46. These members mesh with the outer members in the manner shown, so as to form the complete bearing assembly. Above bearing members 44 is a split ring 48 engaging in a groove in the rotor and held in position by a nut 50 threaded on the upper end of the rotor body.

The rotor body is of somewhat smaller diameter than the inner diameters of the drill pipe 4 and stator section 10, so as to provide a passage for fluid.

Below the lower end of section 10, and between section 12 and the rotor body, is a ring 52 having slots 54 therein which communicate with the space between section 10 and the rotor, and with the first stator stage of the turbine. The stator stages of the turbine are formed of a series of rings 56, rectangular in section, lying one upon the next between ring 52 and shoulder 14, and keyed to the interior wall of section 12. The rotor stages are formed of rings 58, of similar section, lying one upon the other between ring 52 and shoulder 58 on the rotor and keyed to the rotor body. The detailed structure of these rings will be described below. It will be noted that the stator rings have a greater internal diameter than the external diameter of the rotor rings, so that the rotor rings are completely within, and the stator rings completely without, a cylinder whose generatrix is indicated at 60—60 in Figure 5. In any event, for the purposes of one of the important features of the invention, the cooperating rotor and stator blade parts should be so arranged that in the assembled multistage turbine the rotor can slide longitudinally within the stator when the device is disassembled.

Below shoulder 14 there is a space between rotor 6 and section 12, with which communicate passages 62 in the rotor. These passages lead into the hollow lower end 64 of the rotor, which has a lower threaded end 66 for receiving a drill bit.

The device so described operates as follows:

The device is lowered into the ground as shown in Figure 1, either starting at the top of the ground or in a hole already partly drilled. The drill stem or pipe is held against rotation in any suitable manner. Mud of the type ordinarily used in oil well drilling is then pumped down through the drill pipe under pressure. This mud flows through the space between nut 50 and the inner wall of drill pipe 4, passages 30 and 32, the spaces between ribs 24, passage 34, the space below passage 34 between the rotor body and stator section 10, and passage 54 to the first stator stage of the turbine. It then flows through the turbine, passing downward from stage to stage and driving the rotor to cause the bit to turn and drill the hole. After leaving the last

stage, the mud passes into the space below shoulder 14, and then through passages 62 and space 64 to the interior of the drill bit. Then it flows out through the usual holes in the drill bit, as at 68, and upwardly around the outside of the stem in the usual manner.

The arrangement shown is especially intended for easy and quick disassembly, repair and reassembly. To disassemble, the unit is first unscrewed from the drill pipe, nut 50 and split ring 48 are removed, and section 10 is unscrewed and removed from section 12, carrying with it ring 26, spider 22 and both the inner and outer bearing elements. Ring 26 can then be removed and the bearing elements can be taken out for repair or replacement if any is needed.

Stator section 12 with bearing 18 can now be slid downwardly off of the rotor, leaving ring 52 above the rotor turbine blade rings. The stator rings can then be removed from the inside of section 12, and ring 52 and the rotor rings can be removed upwardly from the rotor body. This makes the whole device easy to disassemble, repair and reassemble, since the stator and rotor parts of the turbine can be assembled separately simply by stacking the rings one on the next, and thereafter the rotor can be slide into the stator. Ring 52 and shoulders 14, 58 ensure the proper positioning of the rings with respect to each other.

The procedure described is merely reversed in the reassembly of the unit.

The detailed construction and the method of producing the rotor and stator rings are shown in Figures 4 to 12.

Figures 9 and 10 show the production of a blade forming slot, that is, of a slot forming one blade of a rotor stage of a turbine, in the rotor ring 56. This is accomplished by the use of a grinding wheel 70 having a diameter slightly less than the width of ring 56. This grinding wheel is arranged in a plane 72-72 (Figure 10) which forms a small angle, say 45° or less, with the plane tangent to the surface of the ring at the point of intersection of plane 72-72 with such surface. Plane 72-72 is parallel with the ring axis. The grinding wheel while rotating is moved in this plane from the position shown in solid lines in Figures 9 and 10 to the dotted line position, that is preferably until its shaft 74 abuts against the leading edge 78 of the slot 78 cut by the wheel. This slot will have a substantially semicircular rear wall 80, and thin side walls 82 at each edge of the ring 56. This provides a sloping slot or notch having a rear curved wall. When fluid under pressure is pumped into the slot so formed, it will impart an impulse to rotor ring 56 to turn it clockwise (Figure 5) and will be turned back towards the next stator stage.

Formation of the stator ring 54 is shown in Figures 11 and 12. Grinding wheel 72 is moved within the ring from one side preferably until shaft 74 substantially abuts against the edge of the ring. The angle 72-72 of the plane of the wheel is the same, with respect to the plane tangent to the inner face of the ring, as in cutting the rotor blades. The wheel is moved while rotating from the solid line position shown in Figures 11 and 12 to the dotted line position, in which the diameter across the lower face of the wheel lies in the inner face of the ring, at the leading edge of the slot so formed.

Preferably, rings 54 are made of the same height as rings 56, and this step is carried out at each edge of the ring. This produces in each edge

a slot 84 having a leading edge 86 and a curved rear wall 88 substantially in the form of a quarter circle, the two slots being separated by a thin dividing wall 90. When two of these rings are placed one above the other, as shown in Figure 6, the mating blade-forming slot portions in adjacent edges form a turbine blade having a substantially semi-circular rear wall and thin side walls dividing it from the next blade. Mud flowing into such a blade from one rotor stage will be reversed in its direction of flow and will be directed into the next lower rotor stage so as to impart a further turning impulse to the rotor.

While in Figure 2 there are actually shown only a few turbine stages and only a few sets of bearing elements, it is actually contemplated that a very considerable number of each will be used. For example, turbine drills according to the invention may well have 90 or more turbine stages and 70 or more sets of bearing elements. As these could be all alike, such large numbers are not shown in the drawings.

While I have described herein one embodiment of my invention, I wish it to be understood that I do not intend to limit myself thereby except within the scope of the claims hereto or hereinafter appended.

I claim:

1. An oil well drilling device comprising a turbine having a stator and a rotor, means to secure the stator to a drill pipe, means secured to the rotor to hold a drill bit, said rotor having a passage therein capable of communicating with the mud passage of a drill bit connected thereto, said turbine being adapted and arranged to receive and be driven by drilling mud pumped through the drill pipe, said rotor comprising a rotor body portion, a plurality of superposed rotor rings surrounding said rotor body portion, and means locking said rotor rings against rotation with respect to said rotor body portion, each such rotor ring having a plurality of blade forming slots cut into its outer face, the rear faces of said slots being curved, said slots lying in planes generally parallel to the longitudinal axis of the turbine and forming a small angle with the tangent planes of the rotor rings at the points of entrance of the slots, and said stator comprising a stator body portion, a plurality of superposed stator rings within said body portion, and means locking said stator rings against rotation with respect to the stator body portion, each such stator ring having a plurality of blade forming slots cut into its inner face, the rear faces of said slots being curved, said slots lying in planes generally parallel to the longitudinal axis of the turbine and forming a small angle with the tangent planes of the stator rings at the points of entrance of the slots.
2. An oil well drilling device comprising a turbine having a stator and a rotor, means to secure the stator to a drill pipe, means secured to the rotor to hold a drill bit, said rotor having a passage therein capable of communicating with the mud passage of a drill bit connected thereto, said turbine being adapted and arranged to receive and be driven by drilling mud pumped through the drill pipe, said rotor comprising a rotor body portion, a plurality of superposed rotor rings surrounding said rotor body portion, and means locking said rotor rings against rotation with respect to said rotor body portion, each such rotor ring having a plurality of blade forming slots cut into its outer face, the rear faces of said slots being curved, said slots lying in planes generally parallel to the longitudinal axis of the turbine and forming a small angle with the tangent planes of the stator rings at the points of entrance of the slots.

generally parallel to the longitudinal axis of the turbine and forming a small angle with the tangent planes of the rotor rings at the points of entrance of the slots, and said stator comprising a stator body portion, a plurality of superposed stator rings within said body portion, and means locking said stator rings against rotation with respect to the stator body portion, each such stator ring having a plurality of blade forming slots cut into its inner face, the rear faces of said slots being curved, said slots lying in planes generally parallel to the longitudinal axis of the turbine and forming a small angle with the tangent planes of the rotor rings at the points of entrance of the slots, the blades formed by such slots being generally semi-circular, and the centers of the rotor blades being staggered longitudinally of the turbine with respect to the centers of the stator blades.

3. An oil well drilling device comprising a turbine having a stator and a rotor, means to secure the stator to a drill pipe, means secured to the rotor to hold a drill bit, said rotor having a passage therein capable of communicating with the mud passage of a drill bit connected thereto, said turbine being adapted and arranged to receive and be driven by drilling mud pumped through the drill pipe, said stator comprising a stator body portion, a plurality of superposed stator rings within said body portion, and means locking said stator rings against rotation with respect to the stator body portion, each such stator ring having in at least one edge thereof a plurality of slots each in the general form of a quarter circle, lying in planes generally parallel to the longitudinal axis of the turbine and forming a small angle with the tangent planes of the stator rings at the points of entrance of the slots, and the next stator ring having at least in its adjacent edge a plurality of slots each in the form of a complementary quarter circle and mating with said first slots to form semicircular stator blade slots.

4. An oil well drilling device comprising a turbine having a stator and a rotor, means to secure the stator to a drill pipe, means secured to the rotor to hold a drill bit, said rotor having a passage therein capable of communicating with the mud passage of a drill bit connected thereto, said turbine being adapted and arranged to receive and be driven by drilling mud pumped through the drill pipe, said stator comprising a stator body portion, a plurality of superposed stator rings within said body portion, and means locking said stator rings against rotation with respect to the stator body portion, such stator rings having in both edges thereof a plurality of slots each in the general form of a quarter circle, lying in planes generally parallel to the longitudinal axis of the turbine and forming a small angle with the tangent planes of the stator rings at the points of entrance of the slots, the slots in the meeting edges of adjacent stator rings mating to form semicircular blade slots.

5. An oil well drilling device comprising a turbine having a stator and a rotor, means to secure the stator to a drill pipe, means secured to the rotor to hold a drill bit, said rotor having a passage therein capable of communicating with the mud passage of a drill bit connected thereto, said turbine being adapted and arranged to receive and be driven by drilling mud pumped through the drill pipe, said rotor comprising a rotor body portion, a plurality of superposed rotor rings surrounding said rotor body portion, and means

locking said rotor rings against rotation with respect to said rotor body portion, each such rotor ring having a plurality of blade forming slots cut into its outer face, the rear faces of said slots being curved, said slots lying in planes generally parallel to the longitudinal axis of the turbine and forming a small angle with the tangent planes of the rotor rings at the points of entrance of the slots, said slots in the rotor rings being substantially semi-circular, and said stator comprising a stator body portion, a plurality of superposed stator rings within said body portion, and means locking said stator rings against rotation with respect to the stator body portion, each such stator ring having in at least one edge thereof a plurality of slots each in the general form of a quarter circle, lying in planes generally parallel to the longitudinal axis of the turbine and forming a small angle with the tangent planes of the stator rings at the points of entrance of the slots, and the next stator ring having at least in its adjacent edge a plurality of slots each in the form of a complementary quarter circle and mating with said first slots to form semicircular stator blade slots, the centers of the rotor blades being staggered longitudinally of the turbine with respect to the centers of the stator blades.

6. An oil well drilling device comprising a support part adapted to be releasably secured to the lower end of a drill stem, a rotor having a body including a portion rotatable within said support part, bearing means between said support part and said rotor portion, releasable means on said rotor portion for holding the bearing means with respect thereto, said rotor portion having all its parts above said bearing means other than said holding means of no greater external diameter than the internal diameter of said bearing means whereby said support part and bearing means can be removed upwardly from said rotor portion when said holding means are released, a stator adapted to be releasably secured to the lower end of said support part, said rotor extending within said stator, said rotor and stator having cooperating means thereon forming a multistage turbine, said stator having no part above any part of the rotor of a given external diameter of less internal diameter than such rotor part, whereby said rotor can be slid upwardly out of the stator when the stator is released from the support part, means at the lower end of said rotor to hold a drill bit, said rotor having a passage therethrough connecting the exhaust side of the turbine with the mud passage of a drill bit connected thereto, said turbine being adapted and arranged to receive and be driven by drilling mud pumped through the drill pipe.

7. In a device as claimed in claim 6, said turbine forming means including a plurality of superposed rotor rings around and keyed to the rotor body and having blade forming slots in their outer faces.

8. In a device as claimed in claim 6, said turbine forming means including a plurality of superposed stator rings within and keyed to the stator and having blade forming slots in their inner faces.

9. In a device as claimed in claim 6, said turbine forming means including a plurality of superposed rotor rings around and keyed to the rotor body and having blade forming slots in their outer faces, and a plurality of superposed stator rings within and keyed to the stator and having blade forming slots in their inner faces, said rotor rings lying completely within, and said

stator rings completely without, a common cylinder.
